FRANK L. MASON AND HERMAN GEORGE BENDIX, OF NEW YORK, N. Y.

ARCH-SUPPORTING SHANK FOR SHOES.

1,147,526.

Specification of Letters Patent. Patented July 20, 1915.

Application filed November 24, 1914. Serial No. 873,729.

To all whom it may concern:

Be it known that we, FRANK L. MASON and HERMAN GEORGE BENDIX, citizens of the United States, and residents of the city of New York, borough of Brooklyn, in the county of Kings and State of New York, have invented a new and Improved Arch-Supporting Shank for Shoes, of which the following is a full, clear, and exact description.

This invention relates to shoes and particularly to ladies' turn shoes or those wherein a special arch stiffener or support is necessary or desirable.

Among the objects of the invention, therefore, is to devise a special form of arch support for use especially in connection with ladies' turn shoes and having special advantages with respect to prevention of distortion or twisting of the shoe shank.

A further object of the invention is to provide a novel combination of a special form of shoe shank and coöperating flexible metal stiffener or support.

The foregoing and other objects of the invention will hereinafter be more fully described and claimed and illustrated in the drawings forming a part of this specification in which like characters of reference indicate corresponding parts in all the views, and in which—

Figure 1 is a bottom plan view of one form of shank piece and indicating in dotted lines the position of the stiffener thereon; Fig. 2 is a longitudinal section of the invention shown in Fig. 1; Fig. 3 is a bottom plan view of a modification of the shank piece; Fig. 4 is a top plan view of the same and indicating the stiffener in position thereon; and Fig. 5 is a longitudinal section of the invention shown in Fig. 4.

The several parts of the device may be made of any suitable materials, and the relative sizes and proportions, as well as the general design of the mechanism, may be varied to a considerable extent without departing from the spirit of the invention hereinafter more fully described and claimed.

Our preferred form of shank stiffener or arch supporting plate comprises a pair of side bars 22 connected at their ends by transverse bars 23 and 24, the heel bar 23 having a rearwardly extending tongue 25. The

spacing of the side bars 22 provides a longitudinal groove or slot 26 between the transverse bars. This slot is preferably wider at the heel than the forward end and thereby the bars of substantially uniform width and strength conform substantially to the full width of the shank piece 18 to which the stiffener is connected primarily or initially by clout nails 27 or the like passing upwardly through holes 28 in the extreme ends of the stiffener member and preferably in central longitudinal alinement therewith. The wide structure provided by the heel cross bar 23 insures the parts from relative distortion or twisting in practice, making a more comfortable and satisfactory heel stiffeners in common use.

At any desired distances from the shoulders or points formed by the intersection of the heel bar 23 and the side bars 22, we form a pair of holes for as many screws 30 which are intended to be driven downwardly through the shank piece and through said holes and thence through the sole into the breast portion of the heel, thereby making the connection between the shank stiffener and the other parts of the structure secure against rocking or lateral twisting movement with respect to the heel.

The shank piece 18 of Fig. 1 is one upon the bottom of which is formed a rib 31 by skiving off the side portions as indicated at 32. This rib fits substantially snugly into the tapered slot 26 of the shank stiffener and not only makes a neater construction as to thickness of the shank, but further insures the stiffening or rigidifying of the connecting parts as to lateral strains. The dotted lines in Fig. 1 indicate the relative positions of the shank piece and shank stiffener. The connections in this form of the invention are substantially the same as above described.

In Figs. 3, 4 and 5 we show a slightly modified form of shank piece 18^b, the sides of which are reduced or cut away at 32^a so as to expose the middle portions of the side bars 22 of the shank stiffener. The central rib 31^a of this shank piece extends into and through the slot 26 substantially as in the previous modification. The primary advantage of this form, however, over that form shown in Figs. 1 and 2 is that the purchaser

may plainly see the construction, especially if the slip sole or lining does not obstruct such vision.

We claim:

- 5 1. In a device of the character set forth, the combination of a spring metal shank stiffener including a pair of spaced side bars, a shank piece coöperating with the stiffener and having portions of its upper face skived 10 away leaving a longitudinal rib extending into the space between said side bars, and means securing the stiffener and shank in position.
2. The combination with a spring metal

shank stiffener including a pair of spaced side bars, of a shank piece conforming in width to the shank stiffener and including a rib extending into the space between said side bars, and securing means passing through the stiffener and the shank piece. 15 20

In testimony whereof we have signed our names to this specification in the presence of two subscribing witnesses.

FRANK L. MASON.

HERMAN GEORGE BENDIX.
